UNITED STATES PATENT OFFICE.

SAMUEL G. CRANE, OF TOLEDO, OHIO, ASSIGNOR TO TOLEDO SCALE COMPANY, OF TOLEDO, OHIO, A CORPORATION OF NEW JERSEY.

AUTOMATIC PRINTING SCALE.

Application filed November 21, 1919. Serial No. 339,885.

To all whom it may concern:

Be it known that I, SAMUEL G. CRANE, a citizen of the United States, residing at Toledo, in the county of Lucas and State of Ohio, have invented certain new and useful Improvements in Automatic Printing Scales, of which the following is a specification.

This invention relates to automatic check-printing scales, and has for its object the provision of a machine which will automatically determine the weight of a commodity placed on the platform, print the same upon a check, and issue the check by means entirely within the scale itself, the only operation performed by the operator being the placing of the commodity upon the platform. Thus, the scale automatically furnishes a memorandum of the weight, which in stores and shops may constitute a check to be forwarded to the cashier and in factories forms a permanent record of the weight of the machine part or other commodity that is passed over the platform. When operated in connection with a conveyor, successive commodities may be weighed and printed records of the weights issued in rapid succession without the assistance of or attendance of a weight-checking clerk. Various other uses to which the scale is adapted will readily occur to those skilled in the art.

Another object of the invention is to provide a novel mechanism for so timing the operation of the printing mechanism that said mechanism will not be actuated until after the weighing operation is completed and the weighing parts of the scale are at rest.

With the above and other objects in view, which will readily appear as the invention is better understood, my invention consists of the novel construction, combination and arrangement of parts to be hereinafter more fully described and particularly pointed out in the appended claims.

Reference is to be had to the accompanying drawings illustrating a preferred embodiment of my invention and wherein similar reference numerals designate similar parts throughout the several views.

In the drawings:—

Figure 1 is a rear elevation of the head of an automatic printing scale embodying my invention, the cover plate being removed;

Figure 2 is a detail elevation of a part of the mechanism shown in Figure 1, a portion of the paper-feeding mechanism being shown in section;

Figure 3 is an elevation of a member for positioning one of the type-carrying bars;

Figure 4 is a vertical section taken substantially on the line 4—4 of Figure 2;

Figure 5 is an end view of printing mechanism forming a feature of my invention;

Figure 6 is a detail sectional plan view taken substantially on the line 6—6 of Figure 2 and showing the check-severing knife;

Figure 7 is a perspective view of a part of the knife and a rocking cam for holding the paper in position to be severed;

Figure 8 is a detail view of a paper feed roller pinion and ratchet;

Figure 9 is a detail elevation of a ribbon-feeding pawl and ratchet;

Figure 10 is an elevation of a portion of a timer forming a part of my invention;

Figure 11 is a plan view of the switch operated thereby;

Figure 12 is a perspective view of a re-setting device, a portion of the timer being shown in connection therewith;

Figure 13 is an elevation of a master switch for setting the electric mechanism in operation; and

Figure 14 is a diagrammatic view of the various circuits employed and the devices controlled thereby.

While my invention is adaptable to many different styles and makes of scales, whether the load-offsetting device therein be spring, lever or pendulum, the present embodiment is particularly adapted for use in connection with dial scales, where an indicating hand is adapted to swing over a graduated chart to indicate the weight of the commodity being weighed.

Referring to the drawings in detail, the numeral 1 indicates a scale housing mounted on a column 2 which houses the connections

between the steelyard 4 and the platform lever mechanism (not shown). As the particular weighing or load-offsetting mechanism of the scale forms no part of the present invention, I will describe it briefly, the mechanism being preferably of the type adapted to weigh comparatively heavy loads, the capacity of the scale herein illustrated being 1000 lbs. The pendulum mechanism is one that has been found to successfully demonstrate the capabilities of the invention, and shows a double pendulum scale of a well-known type having a pair of oppositely-swinging load-offsetting pendulums 5, each of which comprises supporting segments 6, the segments 6 being suspended from the lower ends of flexible supporting ribbons secured at their upper ends to the framework of the scale. Intermediate the supporting segments of each pendulum is a somewhat larger segment 8, said segment being connected at its upper end to a flexible metallic ribbon which extends over the arcuate face of the segment and is attached at its lower end to an equalizer bar which is in turn connected to the steelyard 4. The construction of the two pendulums is substantially identical. During the swinging movement of the pendulums to offset the weight of the load the rack 13 connected thereto is moved vertically upward, said rack meshing with a pinion 14 fixed upon an indicator shaft 15 carrying the index hand 16. This pendulum counterbalance mechanism is sufficient to independently offset the weight of all loads within the capacity of the scale.

Supported within the housing 1 and arranged to be held open when the scale is in zero position by means of a lug on the steelyard rod 4 is a master switch 5' in circuit with a source of current C and a solenoid S. The solenoid S is an element of the timing device which forms an important feature of my invention. The timing device may be mounted under the scale platform or at any convenient place within or without the scale, for since it is not mechanically connected to the weighing mechanism or printing mechanism, its location is immaterial. The core 6' of the solenoid carries a rack bar 7 mounted for endwise movement on rollers 8' mounted in stationary uprights 9, as clearly shown in Figure 10. A pinion 10 having its teeth in mesh with those of said rack bar is rotatably mounted upon one of the uprights. Connected to said pinion, and constantly urging it to turn in a direction such as will withdraw the core from the solenoid is a spiral spring 11. The rack bar 7 carries a lug 12 which, when the core is drawn into the solenoid, engages a projection 13 on the slidable bar 14 and thereby moves the bar 14 to open at 15' the circuit controlling the solenoid S (see Figure 11).

Pivoted on the insulated plate 16 is an arm 17 which is yieldingly held in the position in which it is shown in Figure 10 by means of a spring 18. The arm 17 carries a pawl 19 which hangs in the path of the lug 20 attached to the rack bar 7. The pawl 19 is pivoted upon the arm 17 so that it may be rocked out of the way of the lug 20 as the rack is moved by the action of the solenoid, and is provided with a shoulder which engages a complementary portion of the arm when the rack is moved back by the spring 11, causing the contact arm to swing about its pivot.

The pinion 10 is geared to an escapement wheel controlled by a pendulum 22 which retards the movement of the pinion, rack bar, and arm 17. The escapement wheel is connected to the pinion through an overrunning clutch which allows the pinion to rotate during the inward movement of the core 6 without being retarded by the pendulum 22. The timing device is so adjusted that the first of the various circuits controlled thereby will not be closed until a sufficient time has elapsed for the weighing mechanism to come to rest in weighing position.

The indicator shaft 15 of the scale carries a plate 23, the perimeter of which is made up of a series of concentric arcs giving it substantially the form of a stepped spiral, the function of which will appear later. A circular plate D, preferably formed of soft iron, is carried by the indicator shaft 15, and projecting rearwardly from said plate D substantially parallel to the axis thereof is a series of equally spaced pins 24.

Pivotedly mounted upon the bracket 25 secured to the frame of the scale is a hub carrying a substantially semicrescent shaped sector 27. The hub also carries a sector 28 having a series of stepped peripheral projections 29, and rigidly secured to said sector 28 is a plate 30, the outer edge of which is formed of a series of stepped concentric arcs. The center of mass of the parts carried by said hub is so located that the hub and the parts carried thereby tend to rotate in a clockwise direction, but such movement is normally prevented by the weight of the core 31 of the solenoid S¹, the said core being connected to the hub by means of the link rod 32 which loosely passes through an ear 33 on said hub and is headed at 34 to form a lost motion connection therewith.

As the arm 17 of the timer hereinbefore described is moved by the pendulum-controlled action of the spring 11, it engages the contact 35 and thereby closes the circuit which energizes the solenoid S¹. The core 31 is thereupon drawn upwardly and the link 32 slides through the loosely fitting opening in the ear 33. The hub and parts carried thereby are then free to swing and

are moved by gravity in a clockwise direction. At the beginning of this movement the switch 35¹ is allowed to close (see Figures 2 and 12). The closing of this switch 5 energizes the magnet 36 carried upon the free end of the flat spring 37 secured to the frame of the scale. The magnet 36 immediately springs into engagement with the plate D, thus locking the indicator shaft 10 and the parts carried thereby against movement. The sector 28, with the other parts carried by the hub, continues to swing until the concave edge of the stop members 27 engages one of the pins 24, being prevented 15 from rebounding by the inertia of the roller 38 which is journaled at the end of a pivoted arm 39 and engages the edge of the sector C.

Each of the concentric arcs which form the periphery of the plate 22 subtends an 20 angle of 36°, and the plate is mounted on the indicator shaft so that when the load on the platform is from 0 to 99 lbs. in weight the longest arc will lie in the path of a stop 40 carried by a pivoted type-carrying bar 25 41; when the load on the platform is from 100 to 199 lbs. in weight the next shorter arc will lie in the path of the stop 40, and so on. The type 42 on the pivoted type-carrying bar 41 may therefore be arranged to print 30 the hundreds of pounds in any load placed on the platform.

The spaces between the pins 24 register radially with the positioning arcs on the plate 23, and the stop member 27 is so 35 shaped that the angular movement of the sector 28 to bring the stop into engagement with one of the pins 24 is directly proportional to the tens and units of pounds in the weight of the load on the platform.

40 The plate 30 is secured upon the sector 28 in such position and the concentric arcs forming its outer edge are so arranged that when the load on the platform is from 0 to 9 lbs. more than an even hundred, the arc 45 of longest radius will lie in the path of the stop 43 upon the pivoted type-carrying bar 44; when the load is from 10 to 19 lbs. the adjacent arc will lie in the path of the stop, etc. The type 45 on this bar may therefore 50 be arranged to print the tens of pounds in any load placed on the platform.

The sector 28 has a projection 29 corresponding to each of the arcs on the plate 30, and each projection has a series of steps 55 along one edge so arranged that the outermost step will lie in the path of the stop 46 on the pivoted type-carrying bar 47 when the number of pounds in the load on the scale ends in 0; the next outermost step will 60 lie in the path of said stop when the number of pounds ends in 1; and so on. The type 48 on the bar 47 may therefore be arranged to print the units of pounds of any load on the scale.

65 The type-carrying bars 41, 44 and 47 are

provided respectively with weights which tend to swing them about their pivots to bring the stops 43 and 46 into engagement with their corresponding positioning plates.

In order to prevent interference with the movements of the positioning plates, the stops are normally held out of engagement with said plates by means of a member 49 having a solenoid core 50 in its upper end. Engagement of the arm 17 on the timer with 70 the contact 51, which takes place at a pre-determined time after its engagement with the contact 35, closes the circuit which energizes a solenoid S², thereby drawing up the member 49 and allowing the type-carrying bars to swing to printing position. Movement of the member 49 also operates a check-severing and ribbon-feeding device in 75 a manner to be hereinafter set forth.

Further movement of the arm 17 of the 80 timer brings it into engagement with the contact 52, which closes the circuit energizing the solenoid S³, thereby drawing up the core which carries the rack bar 58 meshing with the pinion 59. The pinion 59 has a 85 ratchet and pawl connection with the feed roller 60. When the rack moves upwardly the pawl engages the ratchet and the roller is rotated to feed a strip of paper 54 to the printing mechanism. The printing hammer 90 53 is carried by one arm of a bellcrank lever, the other end of which is operatively connected to the core of the solenoid S³. As the core approaches its limit of upward movement, the printing hammer strikes 95 against the strip of paper 54, momentarily pressing it against an inking ribbon 55 overlying the printing hammer, thereby recording the weight.

Since the end of the arm 17 on the timer 100 moves about a pivot and the rack bar 7 moves rectilinearly, the pawl 19 eventually slips off the lug 20 and the arm is swung back to its original position by the spring 18 and thereby disengaged from the contacts 52, 51 and 35, de-energizing the solenoids S³, S², and S¹.

The overrunning mechanism between the pinion 59 and feeding roller 60 permits said roller to remain stationary during the 110 descent of the rack 58. The core of the solenoid S³ carries an arm 61 having at its end a lateral projection to engage the strip 54 as the core descends and withdraw it sufficiently from the reel 56 over the rollers 57 120 to leave it slack when the core ascends, so that it may be easily drawn between the feed rollers.

The member 49 carries an apertured lug 62 through which passes a rod 63 having a 125 collar secured thereon below the lug 62, a small coil spring being interposed between the lug and the collar. The lower end of the collar 63 is pivoted to an arm 64 rigidly secured to an oval rocking member 65 which 130

with the grid 66 forms a passage for the paper between the feed rollers and the inking ribbon. A pair of lugs 67 extends from the upper portion of the rocking member 65, and lying between said lugs is a projection on the end of a pivoted knife 68. When the member 49 falls, the knife in co-operation with the right-angular edge of a stationary block 69 shears off the printed 10 end of the strip forming a ticket, which falls into the chute 70 and slides into the receptacle 71 located outside the scale housing.

The member 49 also carries a lug 72 which 15 engages a lever 73 having a pawl 74 pivoted thereto to operate the ratchet wheel 75 (see Figure 9). The ratchet wheel 75 is secured to one of the rollers over which the inking ribbon passes (see Figure 1). Thus, as the 20 member 49 falls, it moves the ribbon to present a fresh portion thereof for the next printing operation. When the member 49 descends and engages the type-carrying 25 arms 41, 44 and 47, they are swung out of engagement with the plate 23, the sector 28, and the plate 30. As the solenoid S¹ is de-energized the core 31 falls and the head 34 of the rod 32 engages the ear 33 and swings the sector 28 to its original position, thereby 30 opening the switch 35 and de-energizing the magnet 36 so that the indicating mechanism is free to swing to its original position when the weight is removed from the scale.

35 In order to prevent a repetition of the operation of the printing mechanism when the switch 15 is closed as the solenoid core 6 is withdrawn under the influence of the spring 11, I have provided the re-setting device illustrated in Figure 12. This re-setting device comprises a slidable plate 76 of conducting material, upon which is secured a lug 77 of non-conducting material which is engaged by the arm 17 as it is moved in the 40 operation of the timer. The plate 76, as it is slid longitudinally by movement of the arm 17, is guided by the resilient contact plate 78, connected to the switch 5, with which it remains in slidable engagement. 45 As the plate 76 is moved by the arm 17 it is withdrawn from engagement with a contact plate 79. The contact plate 79 is connected to the switch 15. The contact plate 79 and slidable plate 76 are thus in circuit with the 50 switch 15 and the solenoid S so that when the plate 76 is withdrawn from engagement with the plate 79 the circuit is broken and the solenoid S will not be re-energized even though the switches 5 and 15 be closed.

55 A retractile spring 80 connected at one end to an adjustably mounted bracket 81 and at its other end to an ear on the lug 77 constantly urges the plate 76 into contact with the plate 79. For the purpose of preventing closing of the circuit when the arm

17 returns to normal position and thereby releases the plate 76, I have provided a resilient detent 82 which engages a notch in the plate 76 and thereby holds it out of engagement with the plate 79. 70

The instrument for withdrawing the detent 82 from the notch in the plate 76 is an electric magnet 83 arranged to be energized by a circuit which is closed after the switch 5 is opened by movement of the steelyard to 75 zero position. This circuit closer is clearly shown in Figure 13, and consists of a contact to be engaged by a resilient arm 85 on the movable member of the switch 5. Thus, when the switch 5 is opened the magnet 83 is 80 energized, drawing down the detent 82 and allowing the plate 76 to be drawn by the spring 80 into engagement with the plate 79. The circuit energizing the solenoid S may then be completed by placing a load on 85 the scale platform, thereby closing the switch 5 so that the printing operation will be repeated.

While it will be apparent that the illustrated embodiment of my invention herein 90 disclosed is well calculated to adequately fulfill the objects primarily stated, it is to be understood that the invention is susceptible to variation, modification and change within the spirit and scope of the subjoined claims. 95

Having described my invention, I claim:

1. In a printing scale, in combination, 100 weighing mechanism, a positioning member for determining the position of type carrying means, spaced stop members, connections between said stop members and said weighing mechanism to move said stop members into the path of said positioning member, and means controlled by said weighing mechanism for moving said positioning member into engagement with one of said stop members.

2. In a printing scale, in combination, 110 weighing mechanism, a positioning member, spaced stop members movable with said weighing mechanism, means controlled by said weighing mechanism for moving said positioning member into engagement with one of said stop members, type-carrying means movable into engagement with said 115 positioning member and means controlled by said weighing mechanism for moving said type-carrying means.

3. In a printing scale, in combination, 120 weighing mechanism, a rotatable member connected thereto, spaced pins carried by said rotatable member, a positioning member for determining the position of type carrying means, a curved stop carried thereby, and means controlled by said weighing mechanism to move said positioning member until said stop engages one of said pins. 125

4. In a printing scale, in combination, 130 weighing mechanism, a rotatable member connected thereto, spaced pins carried by

- said rotatable member, a positioning member, a curved stop carried thereby, means controlled by said weighing mechanism to move said positioning member until said 5 stop engages one of said pins, type-carrying means movable into engagement with said positioning member and means controlled by said weighing mechanism for moving said type-carrying means.
- 10 5. In a printing scale, in combination, weighing mechanism, a rotatable member connected thereto, spaced axially extending pins carried by said rotatable member, a swinging positioning member for determining the position of type carrying means, and a substantially semi-crescent-shaped stop carried thereby and adapted to engage one of said pins.
- 15 6. In a printing scale, in combination, 20 weighing mechanism, a rotatable member connected therewith, said rotatable member carrying angularly-spaced stops, a positioning member adapted to swing into engagement with one of said angularly-spaced 25 stops, said positioning member carrying radially-spaced stops, type-carrying means movable into selective engagement with said radially-spaced stops and means controlled by said weighing mechanism for moving 30 said type-carrying means.
7. In a printing scale, in combination, weighing mechanism, a rotatable member connected therewith, said rotatable member carrying angularly-spaced stops, a positioning 35 member adapted to swing into engagement with one of said angularly-spaced stops, said positioning member having a series of concentric arcs of different radii along its edge, and type-carrying means 40 movable into engagement with one of said arcs.
8. In a printing scale, in combination, 45 weighing mechanism, a rotatable member connected therewith, said rotatable member carrying angularly-spaced stops, a positioning member adapted to swing into engagement with one of said stops, said positioning member having a plurality of stepped 50 projections along its edge, type-carrying means movable into selective engagement with said stepped projections and means controlled by said weighing mechanism for moving said type-carrying means.
9. In a printing scale, in combination, 55 weighing mechanism, a rotatable member connected therewith, said rotatable member carrying angularly-spaced stops, a positioning member adapted to swing into engagement with one of said stops, said positioning member having a series of concentric 60 arcs of different radii and a plurality of stepped projections along its edge, type-carrying means movable into selective engagement with said arcs and said projections and means controlled by said weighing mechanism.
10. In a printing scale, in combination, 70 weighing mechanism, a rotatable member connected thereto, spaced axially extending pins carried by said rotatable member, a swinging positioning member, a substantially semi-crescent-shaped stop carried thereby and adapted to engage one of said pins, said positioning member having a series of concentric arcs of different radii along its edge, and type-carrying means 75 movable into engagement with one of said arcs.
11. In a printing scale, in combination, 80 weighing mechanism, a rotatable member connected thereto, spaced axially extending pins carried by said rotatable member, a swinging positioning member, a substantially semi-crescent-shaped stop carried thereby and adapted to engage one of said pins, said positioning member having a plurality of stepped projections along its edge, type-carrying means movable into engagement with one of said projections and means 85 controlled by said weighing mechanism for moving said type-carrying means.
12. In a printing scale, in combination, 90 weighing mechanism, a rotatable member connected thereto, spaced axially extending pins carried by said rotatable member, a swinging positioning member, a substantially semi-crescent-shaped stop carried thereby and adapted to engage one of said pins, said positioning member having a series of concentric arcs of different radii and a plurality of stepped projections along its edge, and type-carrying means 95 movable into selective engagement with said arcs and projections.
13. In a printing scale, in combination, 100 weighing mechanism, a pivoted type-carrying bar, means to limit the pivotal movement of said bar according to the number of even hundreds of pounds of load on the scale, a second pivotal bar, means to limit the pivotal movement of said second bar according to the number of even tens of pounds, less than 100, of load on the scale, a third pivotal bar, and means to limit the pivotal movement of the third bar according to the 105 number of units of pounds, less than 10, of load on the scale.
14. In a printing scale, in combination, 110 weighing mechanism, a positioning member for determining the position of type carrying means, means to normally hold said positioning member out of connection with said weighing mechanism, and means operated from said weighing mechanism to withdraw 115 said holding means and allow said positioning member to move into connection with said weighing mechanism.
15. In a printing scale, in combination, 120 weighing mechanism, a positioning member, 125
- 130

means to normally hold said positioning member out of connection with said weighing mechanism, means operated from said weighing mechanism to withdraw said holding means and allow said positioning member to move into connection with said weighing mechanism, type-carrying mechanism, means to normally hold said type-carrying mechanism out of engagement with said 10 positioning means, and means to withdraw the second said holding means from engagement with said positioning means and thereby allow said type-carrying mechanism to move into engagement with said positioning 15 member.

16. A device as defined in claim 15, in combination with means to actuate the first and second combined withdrawing means in proper sequence.

20 17. A device as defined in claim 15, in combination with electric means to actuate the first and second combined withdrawing means in proper sequence.

18. In a printing scale, in combination, 25 weighing mechanism, a positioning member, means to normally hold said positioning member out of connection with said weighing mechanism, electric means operated from said weighing mechanism to withdraw 30 said holding means and allow said positioning member to move into connection with said weighing mechanism, type-carrying mechanism, means to normally hold said type-carrying mechanism out of engagement 35 with said positioning means, and electric means to withdraw the second said holding means from engagement with said positioning means and thereby allow said type-carrying mechanism to move into engagement 40 with said positioning member.

19. In a printing scale, in combination, weighing mechanism, type-positioning means, means to normally hold said positioning means out of connection with said 45 weighing mechanism, means operated from said weighing mechanism to withdraw said holding means and thereby allow said positioning means to move into engagement with said weighing mechanism, printing 50 type, type-carrying mechanism, means to normally hold said type-carrying mechanism out of engagement with said positioning means, means to withdraw the last said holding means and thereby allow the said 55 type-carrying mechanism to move into engagement with said positioning means, and means for taking an impression from said printing type.

20. The combination with the device defined in claim 19, of means for controlling 60 the sequence of operations thereof.

21. In combination with the weighing mechanism of a scale, a solenoid, means to energize said solenoid upon movement of

said weighing mechanism from zero position, a timing device operated by said solenoid, a plurality of solenoids controlled by said timing device, and printing mechanism controlled by said weighing mechanism and operated by the last said solenoid. 65

22. In a printing scale, in combination, weighing mechanism, a circuit, a normally open switch in said circuit, means for closing said switch upon movement of said weighing mechanism from zero position and 70 opening upon return of said weighing mechanism to zero position, a timer, electric timer operating means in said circuit, a normally closed circuit breaker in said circuit opened by operation of said timer, and 75 means operated upon opening said switch to close said circuit breaker.

23. In a printing scale, in combination; weighing mechanism, a timer circuit, means connected to said weighing mechanism to 80 close said circuit upon movement of said weighing mechanism from zero position, a timer operated upon closing said timer circuit, type-positioning means, an operating circuit therefor, a device for locking said 85 weighing mechanism, an operating circuit for said locking device closed upon movement of said positioning means, type-carrying means, an operating circuit therefor, printing mechanism, and an operating circuit for said printing mechanism, the circuits for operating said type-positioning 90 means, type-carrying means and printing mechanism being successively closed and 95 then opened by said timer.

24. In a printing scale, in combination, weighing mechanism, a timer circuit, means connected to said weighing mechanism to close said circuit upon movement of said weighing mechanism from zero position, 100 a timer operated upon closing said timer circuit, type-positioning means, an operating circuit therefor, a device for locking said weighing mechanism, an operating circuit for said locking device 105 closed upon movement of said positioning means, type-carrying means, an operating circuit therefor, printing mechanism, an operating circuit for said printing mechanism, the circuits for operating said type-positioning 110 means, type-carrying means and printing mechanism being successively closed and then opened by said timer, and a check-severing device operated upon the opening of the 115 circuit for said type-carrying means. 120

25. In a printing scale, in combination, weighing mechanism, a timer circuit, means connected to said weighing mechanism to close said circuit upon movement of said weighing mechanism from zero position, a timer operated upon closing said timer circuit, type-positioning means, an operating circuit therefor, a device for locking said 125

weighing mechanism, an operating circuit for said locking device closed upon movement of said positioning means, type-carrying means, an operating circuit therefor, printing mechanism, an operating circuit for said printing mechanism, the circuits for operating said type-positioning means, type- carrying means and printing mechanism being successively closed and then opened by said timer, a re-setting circuit for said timer, and means to close said re-setting circuit upon return of said weighing mechanism to zero position.

SAMUEL G. CRANE.
